CLIP RETAINING POCKET ATTACHMENT

Walter Albro, Jamestown, N. Y.

Application October 17, 1947, Serial No. 780,340

1 Claim. (Cl. 24—10)

1

This invention appertains to novel and useful improvements in devices adapted to be placed and attached to a pocket piece for retaining clip bearing articles such as pens, pencils and the like.

An object of this invention is to provide means for efficaciously retaining pens, pencils or the like within a pocket.

Another object of this invention is to provide means for carrying out the above mentioned function as well as the function efficaciously securing said means to the pocket piece of a conventional coat, shirt or the like.

Another object of this invention is to provide an extremely simple device of the character to be described which lends itself well to commercial manufacture and common shop practices.

Other objects and features of novelty will become apparent to those skilled in the art, and following the description of the preferred form of the present invention, illustrated in the accompanying drawings, wherein;

Figure 1 is a perspective view of the preferred form of the present invention, portions being broken away to illustrate details of construction;

Figure 2 is a longitudinal sectional view of the invention shown in Figure 1 and taken on the line 2—2 thereof and in the direction of the arrows;

Figure 3 is a transverse sectional view of the invention shown in Figure 1 and taken substantially on the line 3—3 thereof and in the direction of the arrows, and;

Figure 4 is a longitudinal sectional view illustrating details of construction and taken on the line 4—4 of Figure 1 and in the direction of the arrows.

Referring now in detail to the illustrated preferred form of the invention, reference is made primarily to Figure 1 wherein there is disclosed a plate 10 having a folded portion 12 at the bottom end thereof.

The upper portion of the said plate 10 has a folded portion 14 integral therewith which is substantially U-shaped in configuration. Of course, the free edge of the portion 14 which is indicated at 16, may again be folded if so desired.

Countersunk depressions or grooves 18 and 19 in front and back folds respectively may be provided in the plate 10 as well for the purpose of receiving friction securing means, preferably screws 20. Of course, conventional nuts may be associated with the said screws to complete the securing means.

The said securing means is adapted to extend through a pocket patch 22 for retaining the plate 10 in the proper fixed position.

A plurality of grooves 24 is provided in the said folded portion 14 for the purpose of accommodating the clips 26 of various conventional

2

apurtenances such as pens, pencils, combs and the like. Conventional clips 26 are normally provided with a protuberance at the terminal thereof as illustrated in Figure 2. Now, this protuberance is adapted to engage the lowermost extremity or folded portion 16 of the said substantially U-shaped portion 14. This of course, forms an efficacious locking device.

Due to the extreme simplicity achieved by the present invention a further description thereof is deemed unnecessary. However, it is apparent that efficient, simple and convenient means is provided for firmly retaining pens, pencils, combs and the like in a person's pocket regardless of the character of labor performed by him. Jars, shakes and shocks cannot free the pencil, pen or the like from the pocket of the individual utilizing the present invention.

Of course, certain variations may be made without departing from the spirit of the invention. Accordingly, limitation is sought only in accordance with the scope of the following claim.

Having described the invention, what is claimed as new is:

25 A fastener for clip bearing devices for use with a pocket patch comprising a substantially U-shaped member having a longer leg disposed behind the pocket patch and a shorter leg disposed in front of the pocket patch, means for retaining clips on said shorter leg including a plurality of spaced substantially parallel grooves, countersunk fastening means passed through said shorter and said longer legs spaced from the ends of said U-shaped member retaining said U-shaped member fixed to the pocket patch, a longitudinal depression in at least one of said legs extending transversely of said grooves to press against the pocket patch to assist in holding said U-shaped member on the pocket patch, and said shorter leg having a folded lower edge accommodating the lower ends of clips.

WALTER ALBRO.
